UNITED STATES PATENT OFFICE.

CHARLES F. WILLIAMS AND IRA C. WILLIAMS, OF COLDWATER, MICHIGAN.

FLUID-HYDROCARBON BURNER.

1,146,677.

Specification of Letters Patent. Patented July 13, 1915.

Application filed February 27, 1915. Serial No. 11,082.

To all whom it may concern:

Be it known that we, CHARLES F. WILLIAMS and IRA C. WILLIAMS, citizens of the United States, residing at Coldwater, in the county of Branch and State of Michigan, have invented a new and useful Fluid-Hydrocarbon Burner, of which the following is a specification.

The device forming the subject matter of this application is a hydrocarbon burner and the invention aims to provide novel means whereby the flame may be directed at different angles with respect to the vertical.

Another object of the invention is to provide novel means whereby the gas which is to be consumed may be conducted readily to spaced points, thereby permitting the gas to burn, for instance, beneath the spaced lids of a stove or range.

A further object of the invention is to provide a structure of the type above indicated which may be started with a volatile fluid, such as gasolene, kerosene or some like fluid less volatile than gasolene being subsequently employed.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—Figure 1 shows the invention in perspective; Fig. 2 is a top plan; Fig. 3 is a cross section on the line 3—3 of Fig. 2; Fig. 4 is a cross section on the line 4—4 of Fig. 2; Fig. 5 is a fragmental section showing a portion of the head of the gas directing pipe; Fig. 6 is a top plan showing a portion of the means whereby gas and air are mixed, parts being sectioned; Fig. 7 is a fragmental elevation showing a modified detail of the invention.

In carrying out the present invention there is provided a supporting structure embodying an end plate 1, an end plate 2, a partition 3 located between the end plates and side strips 4 uniting the end plates and

the partition. The end plates 1 and 2 are provided with laterally inclined extensions 1' and 2' respectively.

The invention comprises a generating member denoted generally by the numeral 5, the same including manifolds 16 and 16', the ends of the bores of which are closed by screw plugs 50. The manifolds 16 and 16' rest on the inclined extensions 1' and 2' of the supporting frame and are united by a lower pipe 6, an upper pipe 14 and an intermediate pipe 13, these three pipes ordinarily being located in a common plane, which plane is inclined with respect to the vertical as dictated by the inclined edges of the extensions 1' and 2'. The lower pipe 6 communicates with a T 7 and with one end of the T 7 is connected a kerosene pipe 11 in which is interposed a valve 12, the other end of the T being united with a gasolene pipe 8 in which is interposed a valve 10.

The invention comprises a gas supplying pipe 17 disposed transversely of the supporting frame and entering the manifold 16 in approximate alinement with the upper pipe 14. The gas supplying pipe 17 terminates in a depending end supporting a valve 18, the outlet of which is shown at 19. Threaded into the casing 18 is a stem 24 carrying a needle valve constituting a means for controlling the outlet 19. A frame 22 is mounted to slide on the stem 24, the frame including a sleeve 23 surrounding the stem. The frame 22 further includes a disk 21 having a port 20. Owing to the fact that the frame 22 is slidably mounted on the stem 24, the disk 21 may be moved toward and away from the open end 25 of a gas directing member 26 of relatively large diameter, the gas directing member terminating in a transverse head 27.

Journalized for rotation on the end plates 1 and 2 and extended longitudinally of the supporting structure or frame is a burner pipe 29. To facilitate the rotation of the burner pipe, the same is equipped at one end with a handle 33. The burner pipe 29 passes through the head 27 of the gas directing member 26 and through caps 28 which are movably held upon the ends of the head, suitable packings P being employed in connection with the caps and the head 27, in order to prevent a leakage of gas, as will be understood clearly from Fig. 5. That portion of the pipe 29 which lies within the

contour of the head 27 is equipped with a plurality of longitudinal slots 30. External to the head 27 and at some distance therefrom, the pipe 29 is provided with two 5 double sets of jet openings 31. (The jet openings may be replaced by a single slot 51, as shown in Fig. 7, the pipe being there indicated by the reference character 52.)

Surrounding the pipe 29 but spaced therefrom are arcuate deflectors 36 and 36', there being one deflector for each set of jet openings 31. Suspending members in the form of plates 34 may be attached to the deflectors 36 and 36' at the ends thereof, the pipe 29 10 passing through the plates 34, and set screws 35 being employed for holding the plates 34 in adjusted positions on the pipe. At its longitudinal center, each of the deflectors 36 or 36' is provided with a longitudinal groove 37 adjacent which are located deflecting lips 38. The pipe 29 rests upon or is secured to the lips and the jet openings 31 discharge within the contour of the deflector, upon opposite sides of the respective lips. 15

20 The operation of the structure is as follows:—The valve 12 is closed and the kerosene pipe 11 is cut off, the valve 10 being opened and the gasoline pipe 8 being in communication with the pipe 6. After the burner has been started, the valve 10 may be closed and the valve 12 may be opened, after which the structure will operate by kerosene supplied through the pipe 11. The liquid fuel, whatever be its form, traverses 25 the pipe 6 and is converted into gas by the flames burning at the sets of jet openings 31. The gas produced moves longitudinally through one or both of the pipes 13 and 14 and ultimately traverses the pipe 17 and enters the casing 18, the gas passing out through the port 19 in the valve casing and then passing through the port 20 in the disk 21. In this connection it is to be observed that since the frame 22 is slidably mounted 30 on the stem 24, the disk 21 may be moved toward and away from the end 25 of the gas directing member 26, thereby to regulate the amount of air which is admitted along with the gas, it thus being possible to vary the 35 composition of the air and gas mixture. The mixture of gas and air traverses the member 26 and enters the head 27. Thence, the mixture passes into the pipe 29 through the slots 30 and moves in opposite directions to the jet openings 31, at which the gas is ignited and burned.

Passing to Fig. 3 it will be observed that the lips 38 being located between the sets of jet openings 31 serve to direct the mixture laterally, in the first instance, toward the side portions or wings of the deflectors. By means of the handle 33, the pipe 29 may be rotated, thereby shifting the deflectors 36 and 36' circumferentially for the double purpose of directing the flame properly with

respect to the lids of the stove or the like, and for deflecting the flame to a greater or less extent toward and away from the generating member 5.

The groove 37 in the deflector permits a 70 circulation of air underneath the burner tube and the same is thereby cooled.

Having thus described the invention, what is claimed is:

1. In a device of the class described, a 75 support; a burner tube journaled for oscillation thereon and provided with a plurality of sets of burner outlets; a deflector for each set of outlets, the deflectors being carried by the burner tube and being movable with the 80 burner tube; means for converting fuel into gas; means for intermingling air with the gas to form a mixture; and means for supplying the mixture to the burner tube.

2. In a device of the class described, a support; a burner tube journaled thereon for oscillation and provided with a plurality of sets of burner outlets, each set comprising outlets spaced circumferentially of the tube; and a deflector for each set of burner outlets, 85 each deflector comprising opposed surfaces individual to the said circumferentially spaced outlets of each set; and means for securing the deflectors to the burner tube to move therewith. 90

3. In a device of the class described, a support; a burner tube journaled on the support and provided with circumferentially spaced burner outlets; an arcuate deflector partially surrounding the tube; and means for securing the deflector to the tube; the deflector comprising an intermediate portion bearing against the tube between the outlets and providing deflecting surfaces individual to the outlets. 100

4. In a device of the class described, a support having transversely inclined projections; a vaporizing device supported on the projections and inclined laterally with respect to the vertical; a burner tube journaled on the support for oscillation and provided with spaced sets of burner outlets; a deflector for each set of outlets, the deflectors being carried by the burner tube and being movable with the burner tube, the deflectors being adapted to coöperate with the vaporizing device; and means for establishing communication between the vaporizing device and the burner tube. 110

5. In a device of the class described, a 120 support provided with inclined projections; a vaporizing device mounted on the projections and inclined with respect to the vertical; a burner tube journaled on the support for oscillation; deflectors carried by the 125 burner tube, the burner tube being provided with spaced outlets individual to the deflectors; a gas directing member having communication with the burner tube between the deflectors; means for conducting gas 130

from the vaporizing device to a point adjacent the gas directing member; and an adjustable air controlling element operable between the end of the gas directing member and the adjacent end of said means.

6. In a device of the class described, a support; a burner tube journaled on the support and closed at both ends, the burner tube being provided intermediate its ends 10 with an inlet and being provided with burner outlets upon opposite sides of the burner tube; deflectors carried by and movable with the tube and individual to the outlets; a gas directing member open at one end and including a head in which the burner tube is journaled, the head surrounding the inlet; means for supplying gas to the gas directing member adjacent its open end; and a movable air control operating

between said means and the open end of the gas directing member.

7. In a device of the class described, a support; a burner tube journaled for oscillation thereon and provided with an outlet; a deflector carried by the tube and movable therewith, the outlet being arranged to discharge against the deflector; means for supplying fuel to the tube; and means for rotating the tube.

In testimony that we claim the foregoing 20 as our own, we have hereto affixed our signatures in the presence of two witnesses.
